UNITED STATES PATENT OFFICE.

CARL MAYER, OF OESLAU, GERMAN

FURNACE FOR BURNING GLASS, PORCELAIN, AND THE LIKE ARTICLES

No. 858,738.

Specification of Letters Patent.

Patented July 2, 1907.

Application filed December 17, 1906. Serial No. 348,186.

To all whom it may concern:

Be it known that I, CARL MAYER, a subject of the Duke of Saxe-Coburg-Gotha, and a resident of Oeslau, in the Duchy of Saxe-Coburg-Gotha, German Empire; have invented certain new and useful Improvements 5 in Furnaces for Burning Glass, Porcelain, and the Like Articles, of which the following is an exact specification.

My invention relates to a furnace for burning glass, 10 porcelain, majolica, stone-ware and the like articles, more especially to the so-called drawing muffle-furnaces. As known in such furnaces the articles are subjected to a high heat and arrangements must be provided for putting in or introducing the articles to be burned 15 in a space or room and discharging them therefrom, which shows red heat. The devices serving for such introduction and discharge of the articles are, as usual, arranged within the burning chamber and undergo therefore a quick destruction due to this high heat. This 20 defect of the furnace arrangements as hitherto in use shall be removed by my invention, which permits of a continuous heating of the articles to be burned by fitting the furnace with two feeding arrangements, arranged outside of the heating chamber and adapted to be reciprocated vertically and horizontally. By this way the 25 feeding devices are exposed to the high heat for a short time only, and a continuous feeding of the articles is maintained without the feeding devices being liable to injury by heat.

30 To make my invention more clear, I refer to the accompanying drawing, in which:

Figure 1 is a vertical longitudinal section of a convenient constructional form of my furnace, Fig. 2 is a vertical cross section on line C—D of Fig. 1, Fig. 3 is a 35 cross section on line E—F of Fig. 1.

Same parts designate same reference letters throughout the drawings.

a is the masonry and b is a fire room serving for heating the heating room. The latter is formed by the 40 burning chamber b' and the preheating chamber c.

c' is a refractory lining provided with heating drafts or channels d' d' d'. These channels are partitioned by partitions e thus arranged as to impart movement to the fire gases away from the fire-room b to the 45 channel d, and from there below the bottom of the burning chamber b into the channel d' and then to d'' and d'', as indicated by the curved arrows. d'' is an exhaust channel through which the fire-gases are discharged into the main exhaust draft. The undivided bottom 50 of the burning chamber is, as will be seen arranged in the same level with the slotted bottom of the preheating chamber.

The preheating chamber just described is arranged on the righthand side of the furnace. On the lefthand 55 side the cooling chamber c' for cooling the articles when

burned is built up. n are ribs or tongs extending through the cooling, heating and preheating chamber. The opening g in the masonry permits of the cooling air to enter the channels g' which are provided with partitions g'' as to conduct the cooling medium around the 60 cooling chamber, as indicated by the arrows. The cooling air is discharged through the channels h into the main exhaust draft h'.

Within the preheating chamber and the cooling chamber the feeding devices are partially located and 65 constructed in the manner as will now be fully described. The introducing device is formed by a carriage or truck i' provided with pulleys i' running therewith on a rail k placed in the hole p below the bottom of the preheating chamber. The rail is carried 70 on both of its ends by pivoted levers l, adapted to raise and to lower the carriage i'. On their outer ends the levers are connected with chains l' diagrammatically represented and guided over pulleys l'' and provided with a counter-balance l''. The truck i' projects 75 through a slot r' in the bottom of the preheating chamber and allows to carry receptacles or burning baskets m intended to receive the articles to be burned. At its inner end the carriage i' is provided with a projecting arm or jib o of sufficient length, and at its outer end a 80 handle serves for operating the carriage. As will be seen from the drawing in the same manner a carriage or truck i' is partially located in the cooling chamber and beneath the same, and fitted with an arm or jib o for the purpose as hereinafter will be indicated. 85

The muffle furnace as described works in the following manner:—It is supposed that the cooling chamber, the burning and the preheating-chamber are filled up with vessels or burning baskets m containing the articles to be burned. The baskets rest on the ribs n and shall be fed through the muffle in the direction of the arrows x. The carriage i' is illustrated in its utmost righthand and simultaneously lifted position, the jib o extending into the burning chamber. The burning baskets m are raised off from the ribs n in the cooling 90 chamber and in the burning chamber said baskets which interfere with the jib o. The carriage i' is moved in the direction of the arrow x for a certain distance, for instance the length of a basket and then lowered to put anew the baskets on the ribs. The carriage alone 100 is then moved further till the jib o is perfectly removed from the burning chamber. Now the truck i' is lifted, the remaining burning baskets of the muffle are raised off from the ribs and advance for the same length as before the baskets by means of the carriage i'. By 105 lowering the rail k and truck i' the baskets are put again on the ribs; the carriage i' can now move backwards as to prevent the jib o from being exposed to the red heat of the burning chamber. In this manner the baskets are conducted through the muffle and the feed- 110

ing devices will be subjected to the injurious heat of the heating chamber for a short time only, each time when feeding takes place.

It may be pointed out that the proper structure of the trucks can be changed and adapted to the special requirements prevailing in the working of the furnace. Modifications in this direction can be provided without departing from the feature of my invention. The arms σ and τ^3 if required can be fitted with an inner 10 cooling by using a tube-like jib and introducing water therein. Also the feeding truck can be modified. Of course the track k may consist of two rails. An essential advantage is furthermore obtained by heating the burning chamber from beneath, offering no disturbances in heating and permitting of a constant and gentle feeding of the articles. Such a heating chamber is also able to be heated directly.

Having thus fully described the nature of this invention, what I desire to secure by Letters Patent of 20 the United States is:—

1. A muffle furnace for burning glass, porcelain and the like articles, comprising in combination: a burning chamber, a preheating and a cooling chamber arranged axially with each other, the burning chamber having an 25 undivided bottom and being heated from beneath, an introducing device located outside of the heating chamber and adapted to be reciprocated vertically and horizontally, and extending through the slotted bottom of the preheating chamber, a discharging device located outside of the 30 burning chamber and adapted to be reciprocated vertically and horizontally, and extending through the slotted bottom of the cooling chamber.
2. In a muffle furnace for burning glass, porcelain and the like articles, comprising a burning-preheating- and cooling-chamber, an introducing- and a discharging-device, each consisting of a truck located outside of the burning-chamber below the preheating and cooling chamber and extending through the slotted bottoms of said chambers, and having an arm or jib to put therewith articles to be burnt 35 in the burning chamber and to remove them therefrom respectively, rails carrying the truck and means carrying the rails and adapted to raise and lower the truck.
3. In a muffle furnace for burning glass, porcelain and the like articles, comprising a burning-, preheating- and

cooling-chamber: an introducing- and a discharging-device, each consisting of a truck located outside of the burning chamber below the preheating and the cooling chamber and extending through the slotted bottoms of said chambers, and having an arm or jib to put there-with articles to be burnt in the burning chamber and to remove them therefrom respectively, rails carrying the truck, pivoted levers carrying the rails and permitting to raise and lower the truck for feeding the articles to the burning chamber and discharging them therefrom. 45

4. A muffle furnace for burning glass, porcelain and the like articles, comprising: a burning-, a preheating- and a cooling-chamber, having their bottoms in the same level and being provided with ribs on their bottoms, from which the articles to be burnt are carried, and partitioned draughts or channels for conducting the fire-gas and cooling-air respectively around the burning- and preheating-chamber and the cooling-chamber. 55

5. A muffle furnace for burning glass, porcelain and the like articles, comprising a burning-, preheating- and cooling-chamber, the cooling chamber having an undivided bottom, and the bottom of said chambers being provided with ribs, draughts or channels for leading the fire-gases around the burning- and preheating chamber and around the cooling-chamber, an introducing device and a discharging device located outside of the burning chamber and provided with arms or jibs for feeding the articles to be burnt to the burning chamber, and means for lowering and lifting the introducing- and discharging-device. 65

6. A muffle furnace for burning glass, porcelain and the like articles, comprising a burning-, preheating- and cooling-chamber axially arranged, the bottom of the burning chamber being undivided and the burning chamber being heated from beneath, partitioned draughts or channels for conducting the fire-gases and the cooling air respectively around the burning and preheating chamber, and cooling-chamber, an introducing device arranged outside of the burning-chamber and extending through the slotted bottom of the preheating chamber, and provided with a jib, and a discharging device located outside of the burning chamber in the manner of the introducing device, rails carrying both the devices and levers which support the rails and permit to lift and lower said devices. 75

In witness whereof I have hereunto set my hand in the presence of two witnesses.

CARL MAYER.
